UNITED STATES PATENT OFFICE.

DANIEL GOLDSMITH, OF NEW YORK, N. Y.

DESIGN FOR A FINGER-RING SETTING.

SPECIFICATION forming part of Design No. 14,468, dated December 11, 1883.

Application filed July 24, 1883. Term of patent 3½ years.

To all whom it may concern:

Be it known that I, DANIEL GOLDSMITH, a subject of the Emperor of Germany, residing in the city, county, and State of New York, 5 have invented a new and original Design for Jewelry-Settings for Finger-Rings, of which the following is a full, clear, and exact description, reference being had to the accompanying drawings and letters of reference 10 marked thereon, in which—

Figure 1 is a face view of my newly-designed setting, showing it in a ring; and Fig. 2 is an edge view of the ring.

Similar letters indicate like parts in both 15 figures.

The object of my invention is to provide a new design for jewelry-settings for finger-rings and other like articles in which novel and pleasing effects are produced.

20 The setting consists of an oblong body or central section, A, of any suitable substance, surrounded by a border of smaller sections, B and C, having the shape and configuration shown. These sections B and C, it will be 25 seen, form a border or frame around the central oblong section, the sections C being centrally set upon each one of the rectangular

sides of the border or frame, and presenting an annular facet, while the sections B, which fill the remaining space of the border, have 30 each a pyramidal configuration. The surface of the central section of the setting A is rounded and raised above the surrounding border or rim, whereby a handsome effect is produced.

What I claim as my invention is—

35 1. The design for jewelry settings for finger-rings and other like articles, herein shown and described, consisting of an oblong section whose surface is convex from side to side, and surrounded by a border of smaller sec- 40

45 2. The design for jewelry-settings for finger-rings and other like articles herein shown and described, consisting of an oblong section whose surface is convex from side to side, and having thereon an ornamental figure, and surrounded by a border of smaller sections, the oblong convex section being raised above the border.

DANIEL GOLDSMITH.
